UNITED STATES PATENT OFFICE.

HENRY J. BOURNE, OF LYONS, NEW YORK.

GAME DEVICE.

1,150,014.

Specification of Letters Patent. Patented Aug. 17, 1915.

Application filed February 15, 1915. Serial No. 8,425.

To all whom it may concern:

Be it known that I, HENRY J. BOURNE, a citizen of the United States, residing at Lyons, in the county of Wayne and State of New York, have invented certain new and useful Improvements in Game Devices, of which the following is a specification.

My invention relates to improvements in game devices, and the object of the invention is the provision of a game device which will permit the playing of the national game of baseball and which will so closely resemble the game as played upon the field as to produce a highly amusing, interesting and entertaining device.

Another object of my invention is the provision of a game device for playing the game of baseball which will be attractive in appearance to resemble the game, which will be simple and inexpensive of production, which can be easily operated or played and which in every particular will be thoroughly efficient and practical.

With these objects in view, my invention consists of a game device embodying novel features of construction, combination and arrangement of parts substantially as shown, described and claimed.

Figure 1, represents a plan view of the device with the cover closed. Fig. 2 represents a similar view with the cover removed to show the interior construction. Fig. 3 represents a plan view with the cover closed sufficiently to protect the balls and figures contained in the box of the device. Fig. 4 represents a central longitudinal sectional view of the device. Fig. 5 represents an elevation of one of the figures used to represent the players, and Fig. 6 represents a view of one of the balls used in playing the game with indication thereon.

In the drawings: The letter A, designates the box or case which is provided with a suitable sliding cover B, such cover being provided upon its face with the representation C, of the diamond, the series of openings D, which receive the pitcher, catcher, first baseman, second baseman, third baseman and shortstop and the series of outer openings E, which receive the right field, left field and center field players, all of which taken together, compose the nine men used in playing the game. The figure F, is provided which is formed with a pin F', to fit in said series of openings D and E,

it being understood that nine of these players are mounted in said openings. The lid or cover is further provided with longitudinal openings G, which form eight openings and is also provided with the series of openings H, in which are fitted the other nine figures of the opposing side. When the game is being played, nine figures are mounted in the cover and all or a part of the opposing nine figures may be fitted in the openings H, or a series of such players may be placed in the openings J, which are disposed near the bases and 3 of which openings are used in order that three persons may occupy the bases at one time, or only one or two, according to the condition of the game. The cover it will thus be seen, provides the entire field surface of the device and below the cover and in the box, is a pair of longitudinal strips K, which provide the compartment K', which forms a receptacle for the figures when the game is not in use, also the ball passage or chute K², and the pocket K³, into which the balls pass from the ball chute and in playing the game a series of balls L, are used each of which carries a proper indication L², designating the various plays in the game of baseball. The longitudinal strips also provide the ball compartment M, at the upper portion of which is an inclined deflecting strip M', providing in connection with one of said strips the exit opening M², and a pocket N, is provided by means of the strip or wall N', and in said pocket are placed a series of indicators O, O' and O², with indications for strikes, balls and outs, such indicators keeping the strike, ball and out indications.

The box upon its lower wall, is provided with a ridge or rib P, which rests on the table or surface and inclines the box in a suitable manner so that the game is played by simply tilting the board or box up and down.

In using the device, it will be understood that the players are properly stationed upon the lid or cover and that the tilting of the box causes the balls to travel one at a time from the receiving compartment through the outlet, down the ball passage into the pocket at the lower end of said passage and as soon as the ball is deposited in the pocket, it is ascertained what indication it carries and then should it be a hit, a figure is placed in the proper position upon the cover,

should it be a strike, it is properly indicated, should it be a ball, it is properly indicated, and if an out it will be shown by the proper indicator. In plain words, all the balls 5 carry indications of the various plays in the game of baseball, all the balls are placed initially in the receiving compartment and the tilting of the box causes one ball to pass into the chute and be deposited in the pocket at 10 the lower end of said box and in this manner, the game is played exactly like the regular game of baseball and the game can be played by two or more players or one person can perform the game as suits the desires. 15 It will thus be seen that the cover carries the field which has the players mounted thereon and that the box portion has the means for indicating and operating the balls to make the various plays of the game and that an interesting and highly amusing game device is provided.

It will be noted that the tilting of the box causes only one ball at a time to pass into the ball chute and to prevent a rush of the 25 ball, I provide a series of stop pins Q, which

in a manner confine the balls, but still allow their proper movement.

I claim:

The game device herein described, consisting of the box, having a ball container, 30 a container for the figures, a central ball chute or passage, a pocket communicating therewith, a pocket in line with said ball pocket, a series of indicators in said pocket, 35 a series of balls carrying indications and arranged in said ball container and adapted to pass from said container through the chute to the ball pocket, a series of figures provided with pins, a cover fitting on said box and having a diamond and field indicated thereon, and provided with eight 40 openings and a series of openings to receive the figures constituting the players of the two nines.

In testimony whereof I have affixed my 45 signature in presence of two witnesses.

HENRY J. BOURNE.
